CLAIM

The ornamental design for a convertible modular mobile home, as shown.

DESCRIPTION

FIG. 1 is a perspective view illustrating my new design for a convertible modular mobile home, such mobile home being arranged at its normal disposition for transporting the same;

FIG. 2 is a plan view of the convertible modular mobile home shown in FIG. 1;

FIG. 3 is a front end view of the convertible modular mobile home shown in FIG. 1;

FIG. 4 is a rear end view of the convertible modular mobile home shown in FIG. 1;

FIG. 5 is a right side view of the convertible modular mobile home shown in FIG. 1;

FIG. 6 is a left side view of the convertible modular mobile home shown in FIG. 1;

FIG. 7 is a perspective view illustrating my new design for a convertible modular mobile home, such mobile home being arranged at its disposition for habitation;

FIG. 8 is a plan view of the convertible modular mobile home shown in FIG. 7;

FIG. 9 is a front end view of the convertible mobile home shown in FIG. 7;

FIG. 10 is a rear end view of the convertible mobile home shown in FIG. 7;

FIG. 11 is a right side view of the convertible mobile home shown in FIG. 7; and

FIG. 12 is a left side view of the convertible mobile home shown in FIG. 7.
